UNITED STATES PATENT OFFICE.

FRANK JERICHE, OF ELY, MINNESOTA.

RAIL-JOINT.

1,240,727.

Specification of Letters Patent. Patented Sept. 18, 1917.

Application filed March 26, 1917. Serial No. 157,400.

To all whom it may concern:

Be it known that I, FRANK JERICHE, a citizen of the United States, and a resident of Ely, in the county of St. Louis and State of Minnesota, have invented a certain new and useful Improvement in Rail-Joints, of which the following is a specification.

My present invention relates generally to rail joints, and more particularly to a rail joint in the nature of a combined chair plate and fish plate, my primary object being to provide a simple, strong, and durable arrangement capable of effective and efficient use in a temporary, as well as a permanent, sense, my improvements providing for the rigid support and connection of abutting rail ends without the employment of spikes attaching the plates to the rail ties as usual, and thus permitting of either the subsequent removal of the joint forming plates or their permanent connection in operative relation with the rail.

In the accompanying drawing illustrating my invention, and forming a part of this specification:

Figure 1 is a plan view;

Fig. 2 is a vertical transverse section taken therethrough substantially on line 2-2 of Fig. 1;

Fig. 3 is a detailed perspective view of the combined chair plate and fish plate removed, and looking from the under side thereof.

Referring now to these figures, I have shown a pair of abutting rail ends at A and B, in connection with which my improvement is illustrated, the webs of which rails are provided with transverse openings 10 receiving the connecting bolts 11 extending in a manner to be presently described.

The base 12 of the rails rests upon the chair plate 13, as provided by my invention, having at one side of the rails an angular upstanding fish plate 14 overlying the adjacent side of the rail bases, with portions against the adjacent side of the webs of the rails and bearing upwardly against the lower side surface of the rail heads 15, with upwardly projecting upper edge 16 extending partially along the adjacent sides of the rail heads.

The chair plate 13 and the fish plate 14 are formed in one piece, and the former is provided with spike receiving openings 17 adjacent its opposite sides and spaced from

the corresponding side of the rail bases, to engage the lower edge of the angular splice bar 18, having a portion extending upwardly along the webs of the rails opposite the fish plate 14 and provided with openings for alinement with the openings 10 before mentioned of the rail webs to receive the bolts 11, the latter of which also extend through conformable openings in the fish plate 14.

It will be noted that the fish plate 14 is relatively heavier in construction than the chair plate 13, so as to form strong rigid supports for the bolts 11 and around its bolt opening, the fish plate being further reinforced by means of buttresses 19 at its outer sides, positioned as shown in Fig. 1 upon relatively opposite sides of the adjacent ends of the rails A and B, these buttresses as shown extending at their upper ends from the extreme upper edge of the fish plate 14 and projecting at their lower ends materially beyond the adjacent side of the chair plate 13, the bases 20 of the abutments lying in the same horizontal plane with the base 80 or lower surface of the chair plate 13, both of which are similarly provided with series of depending spurs 21 adapted to enter the material of the ties in order to effectively support the parts in operative relation, and 85 securely hold the rails in joined position, temporarily and before the spikes 22 and 23 are driven into the ties.

The abutments 19 have concave sides 24 and the adjacent side of the chair plate 13 90 is provided with inclined spike receiving notches 25 at opposite sides of, and closely adjacent to, the buttresses 19, in order that the spikes 23 when driven into the ties and positioned within the notches 25, will be 95 effectively protected, and will, due to their positions by virtue of the oblique relation of the notches 25 to the sides of the buttresses, resist angular strain, jolts, and jars.

It will thus be noted that the concave 100 sides of the buttresses 19 enable the spikes 23 to be readily driven into the tie in the position shown, that is, closely adjacent the sides of the abutment, and that these abutments not only operate to rigidly brace and 105 strengthen the fish plate 14, but also add materially to the bearing surface of the chair plate upon the tie, whereby with the spurs 21 both upon the lower surface of the chair plate and the buttresses, the parts will be 110

temporarily held in operative position before the application of the permanently connecting spikes.

I claim:

- 5 1. In combination with the abutting ends of adjoining rails, a combined chair plate and fish plate in one piece, the latter of which extends upwardly from one side of the former, at one side of the rails, to the 10 side of the rail heads, and the former of which has spike openings adjacent its opposite side, buttresses integrally connecting the said chair and fish plate at opposite sides of the abutting rail ends, and extending 15 from the top of the fish plate with their lower ends projecting beyond the adjacent side of the fish plate, said buttresses having concaved sides, and said chair plate having its side adjacent the buttresses provided 20 with spike receiving notches disposed in oblique relation to, and closely adjacent, the sides of the buttresses.
2. In combination with the abutting ends of adjoining rails, a combined chair plate and fish plate in one piece, the latter of which extends upwardly from one side of the former, at one side of the rails, to the 25 side of the rail heads, and the former of

which has spike openings adjacent its opposite side, buttresses integrally connecting said chair and fish plate at opposite sides of the abutting rail ends, and extending 30 from the top of the fish plate, said chair plate and said buttresses having their lower surfaces provided with projecting tie engaging spurs.

3. In combination with the abutting ends of adjoining rails, a combined chair plate and fish plate in one piece, the latter of which extends upwardly from one side of the former, at one side of the rails, to the 35 side of the rail heads, and the former of which has spike openings adjacent its opposite side, buttresses integrally connecting said chair and fish plate at opposite sides of the abutting rail ends, and extending 40 from the top of the fish plate, said chair plate and said buttresses having their lower surfaces provided with projecting tie engaging spurs. 45
